ELECTRICAL METER

Harold L. Dsenis, Laguna Beach, and Richard G. Reine-
man, Covina, Calif., assignors, by mesne assignments, to
Simpson Instruments, Inc., Escondido, Calif., a corpo-
ration of California

Filed Feb. 1, 1961, Ser. No. 63,786

Term of patent 14 years

(Cl. D26—1)

FIG. 3

FIG. 1

FIG. 2

FIG. 6

FIG. 4

FIG. 5

FIG. 1 is a perspective view of an electrical meter, showing one form of our new design wherein the meter is rectangular;

FIG. 2 is a side elevational view of the form shown in FIG. 1;

FIG. 3 is a top plan view of the form shown in FIG. 1;

FIG. 4 is a perspective view of an electrical meter, showing another form of our new design wherein the meter is square;

FIG. 5 is a side elevational view of the form shown in FIG. 4; and

FIG. 6 is a top plan view of the form shown in FIG. 4.

We claim:

The ornamental design for an electrical meter, sub-
stantially as shown and described.
